UNITED STATES PATENT OFFICE.

WILLIAM A. PRESTON, OF FORT BRANCH, INDIANA.

REFRIGERATOR.

SPECIFICATION forming part of Letters Patent No. 393,659, dated November 27, 1888.

Application filed April 7, 1888. Serial No. 269,978. (No model.)

To all whom it may concern:

Be it known that I, WILLIAM A. PRESTON, a citizen of the United States, residing at Fort Branch, in the county of Gibson and State of Indiana, have invented certain new and useful Improvements in Refrigerators, of which the following is a specification, reference being had therein to the accompanying drawings.

My invention has relation to certain new and useful improvements upon refrigerators; and it has for its object to provide means whereby a continuous circulation of fresh air throughout the provision-chamber is obtained, the advantage in thus thoroughly ventilating the provision-chamber with fresh air being that the perishable articles placed therein will be kept in a perfectly fresh and prime condition for a greater length of time—a great desideratum with refrigerators.

The invention consists in certain novel features of construction, which will be fully hereinafter described, and particularly pointed out in the claims appended.

In the annexed drawings, Figure 1 represents a vertical sectional view of my improved refrigerator, and Fig. 2 a rear view thereof, a portion of the lower part of the refrigerator being broken away.

In the drawings, the letter A designates the vertical walls of the refrigerator, B the bottom, and C the cover or lid, all of these parts being made double and filled with any of the well-known non-conductors of heat, such as charcoal.

D designates a door leading into the provision-chamber, and E a shelf in the provision-chamber for supporting the articles to be preserved. Over the provision-chamber is located the ice chamber or box F, which is supported in its position by means of suitable cleats, a, secured upon opposite walls of the refrigerator. This ice chamber is located entirely within the refrigerator, a narrow space, G, being left between it and the lid C; and it consists of a vertical double wall, H, a double cover, I, and a double bottom, J, all of which are filled with some non-conducting material, the remaining side K (that opposite the double wall H) being left open, as clearly shown in the drawings.

This ice-chamber is located in such a manner as to form two vertical chambers or passages,

L M, between it and the walls of the refrigerator, the former communicating between the provision-chamber below and the air-passage G above the ice-chamber. The passage M at 55 its upper end is completely bridged or covered over by a horizontal double wall, N, which is supported by the adjacent walls of the refrigerator. Through one of the side walls of the refrigerator, immediately above the division-wall N, is formed a ventilating-opening, O, the size of which is regulated by means of a slide, P, of the usual construction. A screen, Q, stretched across this opening O, serves to keep out insects. R designates a drip pipe, of 65 the usual construction, leading from the ice-chamber to the outside of the refrigerator.

The letters R R' designate two fresh-air-supplying pipes, which extend from one side of the refrigerator in under and in close proximity to the ice-chamber, terminating at their inner ends in downwardly-directed curved mouths, these curved ends emptying the fresh air into the refrigerator near the lower end of passage M. Adapted to close the inlet ends 75 of these air-supplying pipes are valves or slides S, by means of which the supply of fresh air to the refrigerator can be regulated.

As the cold air from the ice-chamber drops down around the downwardly-directed openings of the pipes R', a continuous and adequate supply of fresh air is gently drawn in by suction, the downwardly-curved ends of the pipes serving to bring this result about. The ice-chamber, it is obvious by this construction, may be readily removed for the purpose of cleaning or repairing. When ice is placed in the ice-chamber, the circulation of cool fresh air produced by the same is as follows: The cold air in this ice-chamber, having 80 no other outlet, passes out through the open side K into the passage or chamber M, and from thence down into the provision-chamber below, drawing fresh air in through the pipes R', and forcing the warm and foul air in the 85 provision-chamber up through the passage L upon the other side of the ice-chamber, through the space G, and out at the ventilating-opening O, as clearly shown by the arrows 90 on the drawings.

The object in making the bottom J, the vertical wall H, the cover I, and the horizontal

division-wall N double and non-conducting is to prevent the warm foul air arising from the provision-chamber from being unduly cooled on its passage out of the refrigerator. It is evident that were these walls H I J N made of one thickness of material they would quickly become cold, and thus retard the free outward passage of the warm air by cooling the same as it impinges against the cold walls on its way out. By this arrangement of the ice-box and the double partition N, I obtain a continuous and thorough ventilation of the provision-chamber, thus enabling me to preserve perishable articles in a sweet fresh condition for a greater length of time than in the ordinary refrigerator.

Having thus fully described my invention, what I claim as new, and desire to secure by Letters Patent, is—

- 20 1. The combination, with the refrigerator-casing, consisting of the double non-conducting vertical walls A, one of the said vertical walls being provided with a ventilating-opening, O, the double non-conducting bottom and lid, of the ice-chamber consisting of double non-conducting walls, one side, K, of this chamber being left open, the said ice chamber being located entirely within the refrigerator, so as to leave side spaces, L and M, and the

30 narrow air-passage G above it, fresh-air-supplying pipes, and the horizontal double-wall partition N, arranged over the upper end of the passage M and immediately below the opening O in the refrigerator-wall, as and for the purposes herein fully set forth.

2. The combination of the refrigerator-casing constructed of non conducting walls and provided with a valved exit, O, in one of its vertical walls near the top, an ice-chamber setting wholly within the refrigerator and constructed of double non-conducting walls, one side, K, of this ice-chamber being left open, the ice-chamber forming a horizontal passage, G, between it and the cover of the refrigerator and vertical passages L and M, a bridge-wall 40 supported by the sides of the refrigerator and completely covering over the upper end of the said passage M, the drip-pipes and the fresh-air-supplying pipes emptying into the refrigerator near the lower end of the passage M, 50 substantially as described.

In testimony whereof I affix my signature in presence of two witnesses.

WILLIAM A. PRESTON.
